[57] CLAIM

The ornamental design for a lighting fixture urn body,
as shown and described.

DESCRIPTION

FIG. 1 is a side elevational view of a lighting fixture urn
body showing my new design, the opposite side being a
mirror image;

FIG. 2 is a bottom side perspective view thereof;

FIG. 3 is a top plan view thereof;

FIG. 4 is a bottom plan view thereof; and,

FIG. 5 is a side elevational view thereof as seen from
the righthand side of FIG. 1, the side seen from the left
being a mirror image.

FIG. 1

FIG. 2

FIG. 3

FIG. 4

FIG. 5
